UNITED STATES PATENT OFFICE

155,113

DESIGN FOR A TELEVISION ANTENNA

Victor Trebules, Cleveland, Ohio, assignor to The Gabriel Company, Cleveland, Ohio, a corporation of Ohio

Application September 3, 1948, Serial No. 148,465

Term of patent 14 years

(Cl. D26—14)

To all whom it may concern:

Be it known that I, Victor Trebules, a citizen of the United States, residing at Cleveland, in the county of Cuyahoga and State of Ohio, have invented a new, original and ornamental Design for a Television Antenna, of which the following is a specification, reference being had to the accompanying drawing, forming part thereof, and wherein,

Fig. 1 is an elevational view of a television antenna, showing my new design, the dipoles of the antenna being shown in extended position.

Fig. 2 is a top plan view of the antenna shown in Fig. 1.

Fig. 3 is an elevational view similar to Fig. 1 with the dipoles of the antenna in a collapsed and downwardly folded non-receiving position.

Fig. 4 is an enlarged elevational view of the central housing portion of the antenna, the di-

poles and standard thereof being fragmentarily shown for convenience of illustration.

Fig. 5 is a bottom plan view of Fig. 4, the standard being omitted, and

Fig. 6 is a perspective view of the television antenna, the dipoles and standard thereof being shown fragmentarily.

The dominant features of my design reside in the portions shown in full lines in the drawing.

I claim:

The ornamental design for a television antenna, as shown and described.

VICTOR TREBULES.
